UNITED STATES PATENT OFFICE

156,045

DESIGN FOR A BEDSPREAD

George H. Sheppard, Waycross, Ga.

Application April 22, 1948, Serial No. 145,899

Term of patent 3½ years

(Cl. D92—2)

To all whom it may concern:

Be it known that I, George H. Sheppard, a citizen of Canada, residing at Waycross, in the county of Ware and State of Georgia, have invented a new, original, and ornamental Design for a Bedspread, of which the following is a specification, reference being had to the accompanying drawing, forming part thereof.

The figure is a plan view of a bedspread, showing my new design.

I claim:

The ornamental design for a bedspread, as shown.

GEORGE H. SHEPPARD.
